ATTORNEY

UNITED STATES PATENT OFFICE.

MARSHALL W. GLEASON, OF NEW YORK, N. Y., ASSIGNOR TO GLEASON-TIEBOUT GLASS COMPANY, OF BROOKLYN, NEW YORK, A CORPORATION OF NEW YORK.

DESIGN FOR A GLASS SHADE OR GLOBE.

No. 39,180.

Specification for Design.

Patented March 10, 1908.

Application filed January 21, 1908. Serial No. 412,017. Term of patent 7 years.

To all whom it may concern:

Be it known that I, MARSHALL W. GLEASON, a citizen of the United States, and a resident of the borough of Brooklyn, city and State of New York, county of Kings, have invented a new, original, and ornamental Design for Glass Shades or Globes, of which the following is a specification, reference being had to the accompanying drawing, forming part thereof.

Figure 1 is a side view and Fig. 2 is an inverted plan view, showing my new design.

I claim

The ornamental design for a glass shade or globe, as shown.

MARSHALL W. GLEASON.
